STIRRUP PAD

Francis J. Moore, Minneapolis, Minn.

Application April 13, 1938, Serial No. 201,749

4 Claims. (Cl. 54—47)

My present invention relates to stirrups for riding saddles and, more particularly, to a foot pad attachment therefor.

It is an object of this invention to provide such a foot pad attachment that materially increases the foot-bearing surface of stirrups.

A further object of the invention is to provide a stirrup foot pad attachment having a novel tread for holding a foot resting thereon from slipping.

Other objects of the invention will hereinafter appear.

To the above end, generally stated, the invention consists of the novel construction and arrangement of parts hereinafter described and defined in the claims.

In the accompanying drawing, which illustrates the invention, like characters indicate like parts throughout the several views.

Referring to the drawing:

Fig. 1 is an elevation of a stirrup having the invention attached thereto;

Fig. 2 is a view partly in plan and partly in section taken on the line 2—2 of Fig. 1;

Fig. 3 is a fragmentary view partly in elevation and partly in section taken on the line 3—3 of Fig. 1;

Fig. 4 is a view partly in plan and partly in section taken on the line 4—4 of Fig. 3; and

Fig. 5 is a fragmentary view principally in section taken on the line 5—5 of Fig. 2.

For the purpose of showing the invention in working position, there is illustrated in the drawing a riding saddle stirrup, indicated as an entirety by the numeral 6, with the exception of its transversely elongated foot-supporting member 7, which extends between the lower ends of the yoke arms 8 of the stirrup frame and is formed integral therewith. In the center of the stirrup member 7 is an elongated aperture 9.

Referring now in detail to the improved foot pad 10, the same includes a disc-like body 11, in which is embedded a metal reinforcement in the form of a flat disc 12. This foot pad 10 rests on the stirrup member 7 between the yoke arms 8, and it is important to note that it extends materially both forwardly and rearwardly of front and rear edges of said member, respectively.

The foot pad is rigidly but detachably secured to the stirrup member 7 by a nut-equipped screw-stud 13 and a co-operating clamping bar 14. Said stud 13 is rigidly secured to the reinforcing disc 12 at the center of its under side, depends therefrom and extends through a hole in the foot

pad 10, through the aperture 9 and a central hole in the clamping bar 14.

The clamping bar 14 extends transversely under the stirrup member 7, across the aperture 9 with its end portions engaging said member as a base of resistance. Said clamping bar 14, at its intermediate portion, is upwardly offset into the aperture 9 and thereby holds said bar against endwise shifting movement relative to the stirrup member 7. The nut on the screw-stud 13 impinges against the under side of the clamping bar 14 and together with said stud holds the disc 12 and the clamping bar 14 drawn toward each other and thereby securely holds the foot pad 10 on the stirrup member 7. By reference to Fig. 3 it will be noted that the metal disc 12 overlaps the stirrup member 7 at the ends of the aperture 9 and thereby holds the respective portions of the body 11 clamped onto said member.

On the upper face of the body 11 is a novel tread 15 comprising a plurality of concentric cups 16, as shown three, outer, intermediate and inner. The sides of the cups 16 are made progressively lower from the outer to the inner thereof.

The entire foot pad 10 and its tread 15 is in the form of a single piece of molded rubber, and by reference to Fig. 3 it will be noted that the perimeter of the metal reinforcement extends under the outer cup 16 and affords a rigid support therefor.

Formed in the metal disc 12 is a plurality of holes 17 through which the rubber forming the body 11 extends and forms a plurality of ties 18 that connect the members of the body 11 on each side of the metal disc 12. In addition to the ties 18, the body 11 is further secured to the metal disc 12 by rubber that flows into the interstices in said disc at the time the foot pad 10 is molded.

As the radial strains from a foot resting on the tread 15 is greater on the wall of the outer cup 16 than on the walls of the other cups 16, said wall of the outer cup 16 is made somewhat thicker to add to the rigidity thereof.

A foot resting on the circular rims of the tread 15 will be frictionally held against slipping in all directions in a plane parallel to the foot pad 10. Furthermore, with the ball of the foot resting on the concave surface of the tread 15, formed by the inwardly decreasing height of the side of the cups 16, said foot will also be held thereby from slipping. By standing on the tread 15 or otherwise pressing the foot thereon, the rims of one or more of the cups 16 will be expanded and form a tight joint with the foot, and thereby form a partial vacuum in the cup 16, and the

suction thus produced will materially assist in holding the foot from slipping on the tread 15.

When applying the foot pad 10 to a stirrup 6, the nut on the screw-stud 13 will be tightened 5 sufficiently to cause the metal reinforcing disc 12 to slightly compress the portion of the body 11 lying between said disc and the stirrup member 7 and thereby securely attach the foot pad 10 to the stirrup 6 and hold the same against relative 10 shifting movement.

Obviously, the foot pad 10 materially increases the foot-engaging surface of the stirrup 6 both forward and rearward of the stirrup member 7, and thereby more securely holds the foot relative 15 to the stirrup 6 and at the same time adds to the riding comfort of the foot resting in the stirrup 6.

From what has been said, it will be understood that the invention described is capable of modifications as to details of construction and 20 arrangement within the scope of the invention herein disclosed and claimed.

What I claim is:

1. A foot pad of the class described comprising a rubber body member applicable to the foot-

engaging member of a stirrup and extending materially forwardly and rearwardly thereof, a metal reinforcement supporting said body outwardly of said foot-engaging member, and means for attaching said pad to the stirrup. 5

2. The structure defined in claim 1 which further includes, an upstanding relatively soft rubber flange on the upper surface of the body member, said flange being endless and unbroken.

3. The structure defined in claim 1 which further includes, inner and outer upstanding relatively soft rubber flanges on the upper surface of the body member, each of said flanges being endless and unbroken, the outer flange being higher than the inner flange. 10

4. The structure defined in claim 1 which further includes outer, intermediate and inner substantially concentric upstanding relatively soft rubber annular flanges on the upper surfaces of the body member, each of said flanges being endless and unbroken, the height of said flanges being progressively lower from the outer flange to the inner flange. 15 20
